US0D1029788S

(12) **United States Design Patent** (10) **Patent No.:** **US D1,029,788 S**
(45) **Date of Patent:** **** Jun. 4, 2024**

(54) **VOICE MASKING HEADPHONE**

(71) Applicant: **3M INNOVATIVE PROPERTIES COMPANY**, St. Paul, MN (US)

(72) Inventors: **Douglas W. Fletcher**, Woodbury, MN (US); **Jason T. Lunn**, Mahtomedi, MN (US); **Gregory G. Jager**, Oakdale, MN (US); **Jacob T. Lusson**, Richfield, MN (US); **Eric O. Hemberg**, Sha Tin (HK)

(73) Assignee: **3M Innovative Properties Company**, St. Paul, MN (US)

(**) Term: **15 Years**

(21) Appl. No.: **29/805,033**

(22) Filed: **Aug. 24, 2021**

(51) LOC (14) Cl. **14-01**

(52) U.S. Cl.

USPC **D14/205**

(57) **CLAIM**

The ornamental design for a voice masking headphone, as shown and described.

DESCRIPTION

FIG. 1 is a perspective view showing the new design for a voice masking headphone;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The portions of the voice masking headphone in FIGS. 1-7 shown in broken lines adjacent the shaded areas represent the bounds of the claimed design while all other broken lines depict environment all broken lines form no part of the claimed design.

1 Claim, 5 Drawing Sheets
